UNITED STATES PATENT OFFICE.

GEORGE M. CONDIT, OF WATERVILLE, CONNECTICUT, ASSIGNOR TO THE AMERICAN PIN COMPANY, DIVISION SCOVILLE MANUFACTURING COMPANY, OF WATERBURY, CONNECTICUT, A CORPORATION OF CONNECTICUT.

METHOD OF MANUFACTURING FIXTURE STEMS.

Application filed October 17, 1925. Serial No. 63,172.

This invention relates to a method of manufacturing fixture stems, and more particularly to the fixture supporting end of the stem. The stem to which the invention relates is the well known part of a lighting fixture commonly connected to a junction box or other support and which in use is associated with a canopy through which the fixture stem extends and is adapted to support a lighting fixture in any of the customary manners. Heretofore so far as I am aware, this type of fixture stem at the lighting fixture end thereof has been provided with a connecting member to which the lighting fixture is suitably attached. This connecting end has been affixed to the lighting fixture stem in various manners and difficulty has been experienced in the use of the stem by the parts becoming loose or disconnected. The object of my invention is to overcome this difficulty and to provide a fixture stem so formed at the fixture support end thereof that there is an eye or loop made integral with the body of the tube forming the stem, whereby an article more attractive in appearance is provided as well as one in which there is no possibility for the parts to become loose or separated, and to therefore, support the fixture in an insecure manner or permit the fixture to fall.

In carrying out the invention the fixture stem is made from a tube which is preferably re-drawn to provide an end section which is relatively heavier than the body of the tube. The reinforced end section is then formed as hereinafter described into a loop which is integral with the tube and provides an eye from which a lighting fixture may be supported in any desired manner. The lighting fixture stem at its opposite end is connected to a junction box or other support in the usual manner and the construction of this end of the fixture stem will be hereinafter described, but forms no part of my invention.

In the drawing, Figure 1 is an elevation of the end of a tube from which my improved lighting fixture stem is formed.

Fig. 2 is an end elevation of the same.

Fig. 3 is an elevation of the end of the fixture stem after the same has been drawn or spun to form a knob therein.

Fig. 4 is an end elevation of the same.

Fig. 5 is an elevation showing the end of 55 the fixture stem after the drawn or spun portion has been flattened.

Fig. 6 is an end elevation of the same.

Fig. 7 is an elevation of the end of the fixture stem after apertures have been 60 reamed in the flattened end thereof.

Fig. 8 is an end elevation of the same.

Fig. 9 is a side elevation of the fixture stem after the flattened end thereof has had the outer parts rounded to form a loop 65 therein.

Fig. 10 is an end elevation of the same.

Fig. 11 is an end elevation of the fixture stem after a bead has been spun at the end 70 of the body of the tube.

Fig. 12 is an end elevation of the same.

Fig. 13 is an elevation and partial section of the complete fixture stem, and

Fig. 14 is an elevation and partial section showing another form of the end of the 75 stem for connection with a junction box or other support.

Referring to the drawing it will be seen that in carrying out my invention, the fixture stem made in accordance therewith is 80 constructed from a tube 20 of brass or other similar material. The tube is preferably re-drawn as indicated in Figures 1 and 2, so that the closed end 21 of the tube is of relatively greater thickness than the cylindrical body portion of the tube. After 85 thus re-drawing the tube blank, the reinforced end thereof is suitably drawn or spun to form a spherical knob 22 therein. Those portions lying between the end of the knob and the body of the tube being inclined or tapered as clearly indicated in Figures 3 and 4 of the drawing. The drawn or spun end of the tube, that is the spherical end 90 thereof is flattened as indicated at 23 in Figures 5 and 6 of the drawing. This flattened portion at the end of the tube is then reamed to provide a centrally disposed opening 24 as shown in Figures 7 and 8. After the apertures 24 are provided in the 95 flattened sides at the end of the tube, the outer portions thereof are rounded to form a loop 25 in such a manner that the edges 26 are brought together as is illustrated in Figures 9, 10 and 13. In so doing as will 100 be understood, there are flattened inner edges 27 defining a portion of the apertures 24 and also defining an aperture 28 through

which the lead wires may be carried from the stem to the lighting fixture. As illustrated in Figures 11 and 12, the end portion of the body of the stem is then suitably spun to form a bead 29 therein. As will now be appreciated this forms an end to the lighting fixture stem which is integral therewith and provides an eye for the connection of the lighting fixture, and furthermore, is of an ornamental appearance.

The stem as hereinbefore described may be provided at its opposite end with a socket connection 30 as indicated in Figure 13 or a stud connection 31 as indicated in Figure 14 for securing the same to a junction box or other support. In either event, the stud or socket connection is preferably made of steel and with a circumferential groove 32 into which the edge portion of the cylindrical body of the stem is suitably pressed to securely connect these parts one to the other. However, as hereinbefore stated, the construction at this end of the stem forms no part of my present invention. It will also be obvious as indicated in Figure 14, the stem in a suitable position is provided with a hole or opening 34 through which the lead wires are threaded so as to pass from one end of the fixture stem to the other end interiorly thereof.

I claim as my invention:—

1. The herein described method of making a fixture stem from a tube blank which consists in drawing the tube blank to provide a reinforced section therein, then spin-

ning the tube blank to form a knob in the reinforced section thereof, and then forming a loop in the said knob.

2. The herein described method of making a fixture stem from a tube blank which consists in first drawing the tube blank to provide a thicker section at the end thereof, then spinning the thick end of the tube to form a knob, then flattening the knob, and then reaming the flattened knob to form a loop thereof.

3. The herein described method of making a fixture stem from a tube blank which consists in first drawing the tube blank to provide a thicker section at the end thereof, then spinning the thick end of the tube to form a knob, then flattening the knob, then forming openings in the flattened sides of the knob, and then rolling the outer portions of the flattened knob to form a loop thereof.

4. The herein described method of making a fixture stem from a tube blank which consists in first drawing the tube blank to provide a thicker section at the end thereof, then spinning the thick end of the tube to form a knob, then flattening the knob, then forming openings in the flattened sides of the knob, then rolling the outer portions of the flattened knob to form a loop thereof, and then spinning the end portion of the tube to form a bead thereon.

Signed by me this 2nd day of October, 1925.

GEORGE M. CONDIT.
